(57) **CLAIM**

The ornamental design for a clipboard, as shown and described.

DESCRIPTION

FIG. 1 is a perspective view of the clipboard showing the front and right side of our new design;

FIG. 2 is a rear view of the clipboard of FIG. 1;

FIG. 3 is a front view of the clipboard of FIG. 1;

FIG. 4 is a right side view of the clipboard of FIG. 1, the left side view is a mirror image of the right side view and is therefore not shown;

FIG. 5 is a top view of the clipboard of FIG. 1;

FIG. 6 is a bottom view of the clipboard of FIG. 1; and, FIG. 7 is an alternative perspective view of the clipboard showing the front and left side of our new design.

The recessed area for label placement depicted by means of broken lines in FIGS. 1, 3, 6, and 7 has been shown for illustrative purposes only and form no part of the claimed design.
